UNITED STATES PATENT OFFICE.

MELANCTHON HANFORD, OF MALDEN, MASSACHUSETTS.

ELEVATOR.

SPECIFICATION forming part of Letters Patent No. 397,912, dated February 19, 1889.

Application filed February 8, 1886. Serial No. 191,174. (No model.)

To all whom it may concern:

Be it known that I, MELANCTHON HANFORD, of Malden, county of Middlesex, State of Massachusetts, have invented an Improvement in Elevators, of which the following description, in connection with the accompanying drawings, is a specification, like letters on the drawings representing like parts.

The object of my invention, relating to elevators, is to provide a certain and effectual means for stopping and supporting the elevator-car in case the ropes or machinery should fail, or if the downward speed of the car should be accelerated beyond the desired limit.

The apparatus comprises a safety car-supporting device, preferably a rope hanging at the side of the car and extending from top to bottom of the well or guides in which the elevator operates and itself connected with a yielding support or cushion—shown in this instance as a piston working in a cylinder of sufficient sectional area to produce a force equal to the weight of the car when the air or other fluid is under moderate pressure in the said cylinder. The car is provided with a clutch or gripping device for engaging the safety support or rope, and the said gripping device is provided with automatic actuating mechanism comprising a speed-governor, by which it is caused to engage the support when the speed of downward movement of the car increases beyond the desired limit. Means are also provided for operating the clutch or gripping device by hand from the interior of the car. The entire safety supporting mechanism is independent of the usual car-operating ropes and mechanism, and does not depend for its operation upon the tension of the said ropes, as is the case with many of the safety appliances heretofore made.

Figure 1 is a side elevation of an elevator-car and safety appliances for supporting the same embodying this invention, the supporting frame-work being omitted for greater clearness; Fig. 2, an elevation on a plane at right angles to that of Fig. 1 of the actuating mechanism and governor for the gripping device, and Figs. 3 and 4 a side elevation and plan view of the gripping device detached

from the car on a larger scale; Fig. 5, an enlarged detail to be referred to.

The safety-support which arrests and sustains the car when the proper hoisting apparatus fails is shown in this instance as consisting of a rope, *a*, sufficiently strong to support several times the weight of the car with its maximum load, and extending from top to bottom of the path traversed by the car *A*. The said support *a* is connected with a yielding or elastic cushioning device, shown as a piston, *b*, (indicated in dotted lines, Fig. 1,) working in a cylinder, *c*, which may in practice be about a foot in diameter and a foot and a half (more or less) in length, and normally contains air at the atmospheric pressure, or other suitable fluid. The piston *b* is normally retained at the upper end of the cylinder by a supporting device, shown as a yielding catch, *d*, (see Fig. 5,) and preferably also by a counter-weight, *e*, connected by a cord or chain passing over a pulley, *e'*, with the piston, the said counter-weight being sufficient to balance the weight of the piston and its rod and the rope *a*. The cylinder is preferably provided with an escape-passage, *c'*, having a safety-valve, *c*², which confines the fluid in the cylinder until it reaches a certain pressure, and then permits it to escape; and the said pipe *c* may also be provided with an inwardly-opening check-valve, *c*³, which permits the fluid to enter when the piston is raised, but prevents the escape of fluid from the cylinder. Thus when a heavy weight is applied to the cord *a* the piston *b* is drawn down, compressing the air below it, which exerts a constantly-increasing pressure until, if the dimensions previously given are employed, when the piston arrives at about three inches from the bottom of the cylinder the pressure is about one hundred pounds to the inch, exerting an upward force on the piston of over five tons, which is far beyond the weight of an ordinary elevator-car with its load, so that if the weight of the car were suddenly applied to the rope *a* it would be arrested gradually and its momentum overcome without shock, the car being brought to rest in a downward movement of about a foot and without a sudden strain on

the rope a , thus differing essentially from the usual safety-stops, which check the car almost instantaneously, if at all, and are likely to be broken by the sudden impulse.

- 5 In order to connect the car A with the safety-support a in case its other supports fail, the car is provided with a clutch or gripping device, preferably connected with the bottom thereof, consisting, essentially, of a stop-plate, 10 f , provided with a shoulder, f' , extending from the side of the car, having a seat or groove to receive the rope and constituting one member of the gripping device. The said plate is also provided with a curved dovetail shoulder, f^2 , and has pivoted upon it the movable member f^3 of the gripping device, which has a dovetail shoulder engaging the dovetail projection f^2 , as shown in Fig. 3, and also has a curved gripping-face, f^4 , provided with a 15 groove or seat for the rope a , the said face being eccentric to the pivot f^5 of the arm f^3 , so that when the said arm is turned upward on its pivot its face approaches the shoulder f' , wedging and gripping the rope a between 20 it and the member f' with a holding force which increases with the upward strain on the rope, or, in other words, with the downward strain on the gripping device derived from the weight and momentum of the car. 25 30 In order to move the member f^3 of the gripping device upward, so as to seize the rope a when the downward speed of the car increases above a certain limit, the said member f^3 is connected with an endless actuating rope, 35 belt, or chain, g , passing over pulleys h h' at the upper and lower ends of the elevator-well, so that the said pulleys are rotated in the upward and downward movement of the car. An upward strain on the portion of 40 the rope g connected with and above the movable member f^3 of the gripping device sufficient to overcome the weight of the said device will raise it and cause the safety-support a to be seized thereby. In order to produce 45 such upward strain on the rope g when the speed of downward movement of the car increases, it is provided with controlling mechanism, shown as consisting of a ratchet, i , fast on the shaft i' , and adapted to be engaged by pawls i^2 on the pulley h , which is itself loose on the said shaft, but through the intervention of the said ratchet and pawls causes the shaft to turn with it in its movement produced by the rope g in the downward movement of the car. The said shaft i' 50 operates through suitable gearing, i^3 i^4 , (see Fig. 2,) a centrifugal governor, k , the arms of which act on a rod or stem, m , which is depressed by the governor-arms when the speed 55 of the said arms increases, so that they are thrown outward by centrifugal force from their supports k' in the well-known manner. The said rod m acts on an arm, o , fixed upon a rock-shaft, p , and provided with a supporting-arm, 60 r r' , shown as jointed, and supporting the weighted end of the rope-checking device, shown as a brake-strap, t , which extends over

the part of the rope g lying in the groove of the pulley h , and is normally held out of contact with the said rope by the support r r' , 70 which practically constitutes a vertical toggle-lever. The support r r' , with its shaft p and arm o , constitutes a detent by which the brake or retarding device t is normally prevented from operating. When the governor-rod m is depressed, the arm o will be moved downward by it and the rock-shaft p turned, which movement will break the joint of the support r r' , the upper part of which rests against the stationary stop r^2 , and the brake-strap will be no longer supported, so that its weight will draw it upon the rope g , instantly checking the same, so that in the further downward movement of the car the gripping member f^3 will be raised relative thereto and grip the rope a , which will then sustain the weight of the car, and will check its momentum and bring it to rest gradually through the action of the cushioning device connected with the said support a . 90

It will be seen that the retarding action of the brake t on the rope g is not variable, increasing and decreasing with the speed of the governor, but that it produces no effect on the rope until the speed of the governor rises to 95 a certain maximum amount, and then the brake is applied with maximum effect, and its action is not removed by the subsequent decrease in speed or stopping of the governor.

In order that the resistance of the pulley h 100 and governor mechanism actuated thereby may not retard the rope g sufficiently to cause the gripping device to act, the said rope g may be held down with a yielding pressure by means of a spring, u , engaging a projection, u' , on the said rope, and an arm or bracket, u^2 , connected with the elevator-car. The movable gripping member f^3 may also be operated by an independent cord, v , carried by suitable pulleys or guides to the interior 105 of the car, and provided with a handle readily accessible to the attendant in the car, who can at once operate the said gripping device and stop the car, if desired, independently of 110 the automatic grip-actuating mechanism previously described. 115

As the rope a is never called into operation in the normal working of the car, and is never bent, it is not subjected to deterioration by age, like the usual hoisting-ropes of the car, 120 and the grip-actuating mechanism is wholly independent of the car-hoisting mechanism, depending for its operation upon the downward speed of the car itself, and not upon the speed of any of the ropes or pulleys forming 125 a part of the normal car-actuating mechanism.

It is obvious that instead of the air-cushion any other yielding supporting device—such as a spring or a series of weights applied successively—might be employed to gradually arrest the downward movement of the supporting device a and weight connected therewith, and that the said safety supporting device a 130

is not necessarily a rope or flexible support acting by tensile strength, but might be a strut or upright connected either at its upper or lower end, or both, with a yielding cushion.

- 5 The pulley e' , for the connection between the piston b and its counter-weight e , may be provided with a squared arbor to receive a wrench or crank for the purpose of raising the piston b after it has been depressed in the 10 operation of stopping the car; or any other suitable means may be employed for raising the said piston and for holding it in its upper position—such, for instance, as a spring in the cylinder, which would act, in conjunction with the elastic pressure of the fluid, to stop the piston.

It will be understood that the cylinder c and shafts i' and p and the governor are supported on suitable beams or frame-work like 20 the pulleys and other overhead portions of the hoisting apparatus, and the framing or support for the said cylinder will preferably be separate from and independent of that for the hoisting-pulleys, so as to stand and afford 25 a support for the car in case the other frame-work should break or give way.

By the use of the ratchet and pawl between the pulley h and the governor-shaft the governor is not operated in the upward movement 30 of the car, so that the upward speed is not necessarily limited.

The dovetail shoulder on the gripping device receives the pressure that is exerted by the members engaging the rope a , and, being 35 formed in the same piece with the stationary member of the gripping device, prevents any yielding of the members with relation to one another, which might take place if the pressure were received on the pivot of the movable member.

The arm o on the rock-shaft p is held up against the tripping-rod m of the governor by a counter-weight, p' , or equivalent.

I claim—

- 45 1. The combination of the safety-support with a cylinder and piston therein connected with said support, and a clutch or gripping device for connecting the car with the safety-support, and a retaining device by which the 50 piston is held at one end of the cylinder until operated upon by the weight of the car applied to the safety-support, substantially as described.

2. The combination of the safety-support 55 and yielding cushion for said support, and for the car and its load when connected with said

support, with a clutch or gripping device connected with the elevator-car, and the automatic actuating mechanism therefor, comprising a rope or band, a speed-governor actuated thereby, and a checking device for said rope or band controlled by the said governor, substantially as described.

3. The safety-support and a cylinder and piston therein connected with said support, 65 the said cylinder being provided with an escape-passage, combined with a safety-valve in said passage, and a clutch for connecting the car with the safety-support, substantially as described.

70 4. The combination of a safety-support with a clutch or gripping device connected with the elevator-car, a rope or band connected with and actuated by the elevator-car, a speed-governor actuated by said band, a checking 75 device for said rope, and a detent for the checking device, and connecting mechanism between it and the speed-governor, arranged to be operated only by an increase of speed of the said governor, substantially as described. 80

5. The combination, with a safety-support, of the clutch or gripping device consisting of a plate provided with a shoulder forming one member of the gripping device, and with a shoulder for engaging the co-operating movable member of the gripping device, combined with the movable member consisting of the pivoted arm provided with an eccentric gripping-face, and a shoulder which receives the pressure when the gripping device is engaged 90 with the safety-support, substantially as described.

6. The combination of the safety-support and clutch or gripping device and its operating rope or band, with a governor and operating-shaft therefor, and pulley loose on said shaft that supports and is operated by the said rope or band, and a ratchet and pawl, one connected with said governor-shaft and the other with the pulley loose thereon, as set 100 forth, whereby the pulley operates the governor-shaft when rotated in one direction, but turns upon said governor-shaft when rotating in the other direction, substantially as described.

105 In testimony whereof I have signed my name to this specification in the presence of two subscribing witnesses.

MELANCTHON HANFORD.
